UNITED STATES PATENT OFFICE.

GEORGE B. PHILLIPS, OF SCHENECTADY, NEW YORK, ASSIGNOR TO GENERAL ELECTRIC COMPANY, A CORPORATION OF NEW YORK.

PROTECTIVE DEVICE.

Application filed June 18, 1918. Serial No. 240,664.

To all whom it may concern:

Be it known that I, GEORGE B. PHILLIPS, a citizen of the United States, residing at Schenectady, in the county of Schenectady, State of New York, have invented certain new and useful Improvements in Protective Devices, of which the following is a specification.

My invention relates to protective devices and more particularly to lightning arresters and has for its object to provide a lightning arrester of the vacuum type in which discharges are prevented from flashing over the electrodes, in which the spark gap cannot be short-circuited, in which the atmosphere within the arrester is not impaired by repeated discharges, and which is in general an improvement over similar devices heretofore known in the art.

20 The novel features which I believe to be characteristic of my invention will be defined in the claims appended hereto, while the features of construction and mode of operation will be understood by reference to 25 the following description taken in connection with the accompanying drawing, in which:

Fig. 1 is a side elevation, partly in section, of a protective device of the vacuum 30 arrester type embodying the novel features of my invention, and Figs. 2 and 3 are sectional views of a portion of the device shown in Fig. 1, showing modifications of my invention.

35 The protective device, as shown in Fig. 1, comprises an evacuated vessel or container 1, containing an atmosphere of a monatomic gas, preferably argon, and, in the construction shown, the vessel 1 is of glass and tubular in configuration. Extending through suitable seals 2 and 3, which are similar in construction to those used in incandescent lamps, are leading-in wires or conductors 4 and 5 respectively which are preferably of the well known Dumet wire. I have shown the seals and conductors 4 and 5 extending into the vessel 1 from opposite ends thereof, but it is understood that this construction is not essential. Mounted or supported upon each conductor 4 and 5 are electrode members 6 and 7 spaced apart to form a spark gap 8 therebetween and of a configuration to form a protected gap in a substantially uniform dielectric field. Electrodes 55 6 and 7, preferably, have proximal surfaces

which are substantially spherical and one electrode, for instance, electrode 7, is of a shape to surround or enclose the other electrode 6 or a portion of said electrode, the electrodes being concentrically disposed within the vessel 1. In the construction shown in the drawing this electrode relation is obtained by forming the outer or surrounding electrode as a cup-shaped member and, as shown, this cup-shaped electrode 7 is horizontally disposed within the vessel equidistant from the walls thereof and secured to the conductor 5 through an offset portion 9. The inner electrode 6 may be spherical, but I prefer a cylindrical configuration with rounded ends. This electrode 6 extends into the enclosure formed by the cup-shaped electrode 7 but is spaced away therefrom so that all points between said cup-shaped electrode and the enclosed portion of said inner electrode are substantially equidistant. In this manner a substantially uniform dielectric field is provided for the spark gap 8. The cup-shaped electrode 7 also serves the purpose of protecting the gap 8 and also the walls of the vessel 1 from the effects of spark discharges.

As a means for connecting the electrodes between a conductor or line 10 to be protected and ground, conducting or cap members 11 and 12 are provided surrounding the ends of the vessel 1 and in conducting relation with conductors 4 and 5 respectively. In the construction of the electrodes as shown, the cup-shaped or outer electrode 7 is adapted to be connected to the line and the inner electrode 6 to ground, so that direct current discharges across gap 8 will take place from the outer electrode 7 to the inner electrode 6.

To prevent heavy discharges or discharges of a continuous character from causing a short circuit of the gap due to partial fusion of the electrodes by the heat of discharge, one or both of the electrodes, but essentially the inner electrode 6, is made of non-short circuit-forming material, by which term, I mean a material which will not cause a short-circuit of the spark gap. For such a material, I prefer to use carbon or graphite. In the structure shown, the outer electrode 7 is of metal such as brass.

It has been found that discharges between electrodes in a vacuum, often flash

over the electrodes, such flash-overs taking place to the leading-in wires or conductors 4 and 5 and particularly over the ground electrode 6 to conductor 4, burning the conductor away, affecting the walls of the vessel 1 and causing damage to the seal 2. I confine the discharge to the gap 8 and prevent the discharge from flashing over this electrode, by insulating means which protects or encloses the conductors 4 and 5. For this insulating means I, preferably, provide extended or elongated seals 2 and 3 so that the conductors are enclosed therein. To particularly prevent discharges from electrode 7, from flashing over electrode 6 to conductor 4, I countersink the tip of seal 2 in the end of the electrode so that the junction between this seal 2 and electrode 6 is protected. I also provide a flash-over protector or barrier 13 which, in the form shown in Fig. 1, is a cup-shaped member surrounding the unenclosed or outer portion of the graphite or ground electrode 6. In Fig. 2, the protector is in the form of a disc member 14 between the electrode 6 and seal 2 having portions thereof extending into the path of the flash-over. The central part of member 14 has an extension countersunk in the end of electrode 6 to suitably protect the junction between the disk 14 and the electrode. In Fig. 3 a further modified form of flash-over protector is provided, consisting of an insulating coating 15 which may be painted or otherwise applied to the unenclosed portion of the electrode 6.

It is a well known fact that the electric discharge between electrodes in an attenuated gas alter the pressure of gas by two phenomena going on at the same time, namely, removal of gas by the so-called clean-up effect and the evolution of gas from the electrodes due to the discharge. The resulting changes of pressure and composition of the gas within the vessel affects the voltage value at which a discharge will occur. I overcome these disadvantages by a treatment of the electrodes which consists in heating them to a high temperature in a suitable receptacle, exhausting the air therefrom and then permitting the electrodes to cool in an atmosphere of the monatomic gas with which the vessel is to be filled. In this manner the electrodes in cooling absorb the monatomic gas and when such electrodes are repeatedly heated by spark discharge within the evacuated vessel 1 and cooled, a minimum effect is observed upon the pressure of the atmosphere within the vessel 1 and no deleterious gases are given off and hence a more uniform arc-over potential can be obtained.

In accordance with the provisions of the patent statutes, I have described the principle of operation of my invention, together

with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In combination with a line to be protected, a protective device connected in circuit between said line and ground comprising an evacuated vessel, a cup-shaped electrode connected to the positive side of said circuit, and a cooperating electrode extending within the enclosure of said cup-shaped electrode and adapted to be connected to the negative side of said circuit, said electrodes being separated to form a spark gap.

2. A protective device comprising an evacuated vessel, a cup-shaped electrode within said vessel, and a cooperating electrode within the enclosure of said cup-shaped electrode and separated substantially equidistant therefrom to form a spark gap, said electrodes being connected in such a relation that a discharge takes place from said cup-shaped electrode to said cooperating electrode.

3. A protective device comprising an evacuated vessel, two cooperating electrodes within said vessel, one surrounding the other and spaced apart to form an enclosed spark gap therebetween, at least one of said electrodes being of carbon free from deleterious gases.

4. A protective device comprising an evacuated vessel, two cooperating electrodes within said vessel, one electrode enclosing the other to provide a spark gap therebetween, conductors secured to said electrodes, insulating means surrounding one of said conductors and means between said insulating means and the corresponding electrode for preventing discharges across said gap from flashing over to said one conductor.

5. A protective device comprising an evacuated vessel, two cooperating electrodes within said vessel concentrically arranged and spaced apart to form a spark gap, and a protecting member adjacent the inner electrode in position to prevent discharges across said gap from flashing over said inner electrode.

6. A protective device comprising an evacuated vessel, two cooperating electrodes within said vessel spaced apart to form a spark gap, conductors secured to said electrodes, insulating means enclosing said conductors and a barrier adjacent one of said electrodes in position to prevent discharges across said gap from flashing over said electrode.

7. A protective device comprising an evacuated vessel, conductors extending into said vessel, seals for said vessel completely en-

- closing said conductors, and cooperating electrodes carried by said conductors adjacent said seals and separated to form a spark gap, the end of one of said seals being countersunk in its adjacent electrode.
8. A protective device comprising an evacuated vessel containing an atmosphere of a monatomic gas, electrodes within said vessel cooperating to form a spark gap, said electrodes containing said monatomic gas and being free from deleterious occluded gases whereby they are capable of operating upon spark discharge without impairing the atmosphere within said vessel and with a minimum effect upon the pressure therein. 15
9. The method of treating electrodes forming a spark gap in an evacuated vessel containing monatomic gas, which consists in heating said electrodes to a high temperature in a receptacle, exhausting the air from said receptacle and permitting said electrodes to cool in an atmosphere of the monatomic gas. 20
- In witness whereof, I have hereunto set my hand this 17th day of June, 1918.

GEORGE B. PHILLIPS.
